UNITED STATES PATENT OFFICE.

ALEXANDER OLSZEWSKI, OF NEWARK, NEW JERSEY, ASSIGNOR TO THE CELLULOID MANUFACTURING COMPANY, OF NEW YORK, N. Y.

MACHINE FOR TREATING COMPOUNDS OF PYROXYLINE.

SPECIFICATION forming part of Letters Patent No. 280,659, dated July 3, 1883.

Application filed May 18, 1883. (No model.)

To all whom it may concern:

Be it known that I, ALEXANDER OLSZEWSKI, a citizen of the United States, and a resident of Newark, in the county of Essex and State 5 of New Jersey, have invented certain new and useful Improvements in Machines for Treating Compounds of Pyroxyline, of which the following is a specification.

The invention relates to improvements in 10 machines for treating compounds of pyroxyline and analogous plastic materials, and has for its object the rapid and effectual conversion or re-conversion of such compounds and the formation of the converted or reconverted material 15 into rods, bars, tubes, &c., all as hereinafter recited and set forth.

The particular nature and operation of my 20 improvements will be readily understood from the detailed description hereinafter presented, reference being had to the accompanying drawings, in which—

Figure 1 is a central vertical section through 25 the machine. Fig. 2 is an elevation of the same. Fig. 3 is a sectional view on the line $x-x$, looking downward. Fig. 4 is an enlarged vertical central section of the plunger. Fig. 5 is an inverted plan view of the same, showing four nozzles. Fig. 6 is an enlarged central vertical section through a plunger having 30 one main outlet and two nozzles; and Fig. 7 is a plan of the same.

In the said drawings, A denotes the head, and B the bed-plate, of the machine, which are suitably connected by and supported upon the 35 columns or bolts C.

The piston (lettered D) forms a part of or is mounted upon the bed-plate B, and is of proper size to snugly enter the water-cylinder E and permit the same to have a vertical movement 40 between the bolts C. The upper end of the piston D is suitably packed to form a water-tight joint, and through the said piston and leading into the cylinder E is a passage, F, which is connected with a suitable source of 45 fluid-supply by the pipe G. Upon the closed end of the water-cylinder E is placed and secured in any convenient manner (in the present instance by the hinged bolts H) the material-cylinder I, which is of proper size to admit the plunger J, and is surrounded by the

annular chamber or jacket K, having an inlet, L, for steam or other heated fluid, and an outlet, M. The material-cylinder I is hollow throughout, and in the present instance a removable disk, N, is placed in its bottom; and, 55 if desired, a sheet of non-conducting material may be placed between the cylinders E and I, the purpose being to prevent the heat from the steam-chamber K from affecting the upper end of the cylinder E. The plunger J depends 60 from the head A and contains a central chamber, O, and passages P. The central chamber, O, is provided with an inlet, Q, and an outlet, R, whereby steam or other heating agent may be passed into and from the chamber, and the 65 piston thus suitably heated to keep the material passing through it in a proper condition, as hereinafter described. In the present instance I employ four passages, P, passing through the plunger J, and the upper ends of 70 the said passages are connected with nozzles S, each having two openings, a b, through the former of which the material is allowed to escape, while in the latter is placed the plug c, which, when removed, permits the introduction 75 of means for cleaning the passage. It is, however, plain that the material may be allowed to escape through both the passages a b, if desired.

In the construction of the plunger illustrated 80 in Fig. 1 the passages P are lined with tubes T, which form part of or are connected with the nozzles S, the lower end of the tubes being threaded and screwed into the bottom plate, x, whereby the said plate and the nozzles are 85 at once secured to opposite ends of the plunger in a rigid position. In the base-piece x of the plunger J are formed concavities e, around the entrance to the passages P, which have the effect of facilitating the movement of the material into the said passages. 90

In Fig. 4, I show the construction of the plunger J in an enlarged view. Upon the horizontal outlets a of the nozzles S may be secured the apparatus for molding celluloid tubes or rods, which is described in my application for Letters Patent of the United States filed April 10, 1883, Patent No. 278,667, dated May 29, 1883, and the material allowed to pass from the same through various outlets; or the nozzles 100

S may be employed in exactly the condition in which they are illustrated in the drawings and a single rod or tube permitted to escape from each nozzle. Around the nozzles S, in 5 proximity to the head A, may, if found necessary, be provided steam-chambers W, in order to retain in a softened condition the material passing through the plunger. It will not be necessary in all cases to employ the steam-chambers W; but they may be found desirable 10 under some conditions of the material.

In Fig. 6, I show a modification of the plunger J, illustrated in the other figures of the drawings, the same consisting in having a single passage, P, through it for the material, the 15 said passage being connected at its upper end with a nozzle having two outlets, W', as indicated, or with a nozzle having any number of outlets desired. The plunger shown in Fig. 6 20 has an annular heating-chamber, Z, encircling the central passage, P, and being supplied with a supply and delivery pipe, (lettered g h, respectively.) According to the construction illustrated in Fig. 6 the upper contracted portion 25 of the plunger J extends through the head A, and is screwed into the lower end of the nozzle S, whereby the said plunger and nozzle are secured upon opposite sides of the head A.

30 In the operation of the invention the cylinder E is first allowed to lower upon the piston D, which carries the material-cylinder I from below the lower end of the plunger J to the position indicated in Fig. 2. The material is introduced into the upper end of the material-cylinder I, the steam or other heating agent having 35 been admitted to the chamber K and the water to the pipe G, whereby the cylinder E is caused to ascend and carry the material-cylinder I upward to the position indicated in Fig. 1, in which position the plunger J (which has become heated by the passage of steam or other heating agent through it) will have entered the cylinder I, and will bear against the material, and by reason of the pressure against it, the heat in the cylinder and plunger, and its movement through the passages P, the same will become plastic and be converted or transformed into a solid homogeneous mass and discharged 45 from the nozzles S. After a large proportion of the material has been forced from the machine through the passages P the cylinder E may be allowed to lower again and an additional charge of material placed in the cylinder I and the operation repeated, as hereinbefore described.

It will appear plain that any one or more of the outlet-passages P may be employed, according to the circumstances attending the use of the machine, and that when a portion of the 60 passages are being used the remaining passages should be plugged up by bolts or plugs, which will extend their entire length, so as to keep them entirely clear of the material, which otherwise might enter the passages, and, becoming hardened therein, prove a source of annoyance.

What I claim as my invention, and desire to secure by Letters Patent, is—

1. An apparatus for converting or reconverting pyroxylene material, consisting of a hydraulic press, an open material-cylinder provided with a heating-chamber, and a plunger adapted to enter the said cylinder, and having one or more outlet-passages for the material, 75 substantially as set forth.

2. An apparatus for converting or reconverting pyroxylene material, consisting of a hydraulic press, a material-cylinder surrounded by a steam-jacket, and a plunger adapted 80 to enter said cylinder, and containing one or more outlet-passages for the material, and a heating-chamber, substantially as set forth.

3. An apparatus for converting or reconverting pyroxylene material, consisting of a 85 hydraulic press, a material-cylinder provided with a heating-chamber, and a plunger adapted to enter said material-cylinder, and containing one or more outlet-passages for the material, said passage or passages being capped with a 90 nozzle for giving form to the discharged material, substantially as set forth.

4. An apparatus for converting or reconverting pyroxylene material, consisting of a 95 hydraulic press, a material-cylinder surrounded by a steam-jacket, a plunger adapted to enter said cylinder, and containing a heating-chamber, and one or more outlet-passages for the material, an outlet nozzle or nozzles capping the passages through the plunger and being provided with a heating-chamber, substantially as set forth.

Signed at New York, in the county of New York and State of New York, this 15th day of May, A. D. 1883.

ALEXANDER OLSZEWSKI.
